UNITED STATES PATENT OFFICE.

FRANK DEAN, OF NEW CASTLE, PENNSYLVANIA, ASSIGNOR OF ONE-HALF TO H. O. DAVIS, OF NEW CASTLE, PENNSYLVANIA.

THILL-COUPING.

No. 913,945.

Specification of Letters Patent.

Patented March 2, 1909.

Application filed June 22, 1908. Serial No. 439,846.

To all whom it may concern:

Be it known that I, FRANK DEAN, a citizen of the United States, residing at New Castle, in the county of Lawrence and State of Pennsylvania, have invented certain new and useful Improvements in Thill-Couplings; and I do hereby declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to new and useful improvements in thill couplings and the object in view is to produce a simple and efficient device of this character which will serve as an anti-rattler.

20 The invention comprises various details of construction, combinations and arrangements of parts which will be hereinafter fully described and then specifically defined in the appended claim.

25 I illustrate my invention in the accompanying drawings, in which:—

Figure 1 is a perspective view of my improved thill coupling showing the parts connected together. Fig. 2 is a sectional view longitudinally through the coupling, and Fig. 3 is a detail view of the loop adapted to be fastened to the shaft or thill.

Reference now being had to the details of the drawings by letter, B designates a coupling member adapted to be fastened to the running gear of a vehicle and is provided with a semi-circular outlined recess D in one end of which is positioned a buffer E behind an overhanging portion of the inclined wall 35 of the recess. The head of said coupling member is preferably cylindrical outlined and flattened upon its upper edge and has a transverse slot F leading into said recess and 40 through which slot the coupling link A is adapted to be inserted. Said coupling link

45 A has lugs H projecting therefrom in alignment with each other and at inclinations to the length of the link, said lugs being adapted to turn within the recess of the coupling member, one of the lugs normally resting against

the end of said buffer. When the lugs are inserted in said coupling, it is necessary to raise the thill to an upright position to allow the lugs to be inserted in the slot. Said lugs are preferably of a width equal to the recess 55 in said coupling member and, after being inserted in place, when the thills are turned down toward a horizontal position, one of said lugs will contact with the under edge of said buffer and hold the parts securely against 60 rattling. In order to prevent foreign matter entering the slot and recess, a closure, designated by letter N, has arms N' which are pivotally mounted upon the pins O carried by said head. Said closure is provided with 65 recessed portions N² in order to fit over the coupling link, as shown clearly in the drawings. Said closure is mounted upon the coupling head in such a manner that it will be normally mounted in closed position with 70 downwardly projecting portions fitting over the upper edges of the head. When it is desired to remove the coupling link, the lugs are thrown to an upright position to be allowed to freely move in the slot.

75 What I claim to be new is:—

A thill coupling comprising a coupling member designed to be attached to the running gear and having a head with a circular outlined recess therein, one end of the recess 80 having an overhanging wall, a buffer positioned in one end of the recess and behind said overhanging wall, the opposite end walls of the head of the coupling member being provided with registering slots, a link 85 adapted for attachment to a thill and having lugs projecting in alignment with each other and adapted to turn within said recess, one of the lugs normally bearing against the end of said buffer, portions of the link on either 90 side of the lugs having bearings in the bottoms of said slots, and a guard plate pivotally mounted upon the coupling member and closing said slots, as set forth.

95 In testimony whereof I hereunto affix my signature in the presence of two witnesses.

FRANK DEAN.
